UNITED STATES PATENT OFFICE.

WILLIAM DEERING, OF LOUISVILLE, KENTUCKY.

IMPROVEMENT IN HAY-PRESSES.

Specification forming part of Letters Patent No. 38,659, dated May 26, 1863.

To all whom it may concern:

Be it known that I, WILLIAM DEERING, of the city of Louisville, State of Kentucky, have invented an Improvement in the Construction of Hay-Presses; and I declare the following specification, with the drawing accompanying and forming part thereof, to be a full and complete description of my invention.

My improvement is intended to be applied to a form of hay-press largely in use in the State of New York and adjoining States, or any other press in which the follower is operated in an analogous way.

The drawing represents one of these hay-presses, with portions of the frame and hay-box removed to show its construction.

A is the frame; B, the hay-box; E, in dotted lines, its top; F, the follower; C, the main lever; D, the fulcrum-levers, a pair being one on each side of C. The fulcrum-levers are pivoted at d to the frame, and to the main lever at c, and the main lever is attached to the follower under its center at a. The power is applied at H by the rope or purchase J, in the direction J f, when as H progresses its upper end will rise, carrying the follower upward, compressing the inclosed hay between it and the top of the box B.

My improvement, which is essential to the smooth and economical working of the ma-

chine, is shown at M M within the box B. The follower F being poised or balanced on its center a upon the lever C, a trifle of unequal pressure of its load on one side of the center will tend to cant it sidewise, causing its edges to bind against the sides of the box and produce a dragging strain and jerking motion upon the motive machinery, requiring a considerable expenditure of power to overcome its resistance. To relieve this tendency, I attach to the opposite sides of the box vertical and parallel slides or guides M M, (from the nature of the drawing they can only be shown on one side,) and fit the follower F to them by grooves g g, accurately cut in its edges, or the vice versa of this arrangement by making grooves in the sides of the box and fitting projections in the edges of the follower to fit within them. In both cases friction-rollers may be applied to relieve friction of the parts.

What I claim as my invention, and desire to secure by Letters Patent, is—

The guides or slides M M, with the grooves g g, in combination with the hay-box B and follower F, in the manner described, and for the purposes set forth in this specification.

WILLIAM DEERING.
